US00D884650S

(12) **United States Design Patent** (10) Patent No.: **US D884,650 S**
(45) Date of Patent: **** May 19, 2020**

(54) **ELECTRICAL CONTACT**

(71) Applicant: **EBARA CORPORATION**, Tokyo (JP)

(72) Inventors: **Kiyoshi Suzuki**, Tokyo (JP); **Jumpei Fujikata**, Tokyo (JP)

(73) Assignee: **EBARA CORPORATION**, Tokyo (JP)

(**) Term: **15 Years**

(21) Appl. No.: **35/505,847**

(22) Filed: **Apr. 6, 2018**

(80) **Hague Agreement Data**

Int. Filing Date: **Apr. 6, 2018**

Int. Reg. No.: **DM/100641**

Int. Reg. Date: **Apr. 6, 2018**

Int. Reg. Pub. Date: **Oct. 12, 2018**

(30) **Foreign Application Priority Data**

Oct. 10, 2017 (JP) 2017-022371

(51) **LOC (12) Cl.** **13-03**

(52) **U.S. Cl.**

USPC **D13/147**

(58) **Field of Classification Search**

USPC D13/154, 133, 148, 182, 110, 118, 120, D13/147, 184, 199; D15/138; D8/364
